Inventor

Thomas Onslow

UNITED STATES PATENT OFFICE.

THOMAS ONSLOW, OF PHILADELPHIA, PENNSYLVANIA, ASSIGNOR TO HORNER BROTHERS, OF SAME PLACE.

DESIGN FOR A CARPET.

SPECIFICATION forming part of Design No. 13,634, dated February 20, 1883.

Application filed January 15, 1883. Term of patent 3½ years.

To all whom it may concern:

Be it known that I, THOMAS ONSLOW, of Philadelphia, State of Pennsylvania, have invented and produced a new and original Design for Carpets, of which the following is a specification.

The nature of my design is fully represented in the accompanying photographic illustration, to which reference is made.

I claim as my invention—

The design for a carpet, as shown.

Witnesses: THOMAS ONSLOW.

THOMAS E. MEAGHER,

GEORGE W. PUGH.
